W. E. Beck, ATTORNEY

UNITED STATES PATENT OFFICE

GEORGE RITNER SCHNORE, OF ELGIN, OREGON

MILK CABINET

Application filed May 28, 1930. Serial No. 456,695.

My invention relates to improvements in milk bottle safes and has for its primary object to provide a safe and sanitary cabinet for the reception of milk bottles.

- 5 A further object of the invention is to provide a safe of the above-mentioned character adapted to be mounted in an opening through the wall of a building having a closure member on the outside and locking 55 means within the safe normally holding the closure member locked, operable by means on the outside of the safe, when a milk bottle is placed in the safe beneath said locking means.
- 10 15 A further object of the invention is to provide a milk bottle safe mounted in the wall of a building, to which access may be had from the inside at all times; but access to the safe from the outside is only possible under 20 certain conditions.

Another object of the invention is to provide a device of the above-mentioned character which is simple and durable in construction, reliable and efficient in operation 25 and inexpensive to manufacture.

Other objects and advantages of the invention will be apparent during the course of the following description.

In the accompanying drawings, forming 30 a part of this specification and in which like numerals are employed to designate like parts throughout the same,

35 Fig. 1 is a front elevation of the safe with the door open,

Fig. 2 is a section taken on lines 2—2 of Fig. 1,

Fig. 3 is a longitudinal sectional view of the same, and,

40 Fig. 4 is a section taken on lines 4—4 of Fig. 3.

In the drawings, wherein for the purpose of illustration I have shown a preferred embodiment of my invention, the numeral 5 denotes the wall of a house or building having an opening 6 therethrough at a place convenient for the use for which it is intended.

45 Referring more particularly to my invention I provide a cabinet consisting of top and bottom walls 7 and 8 and side walls 9

and 10 which are fitted in the opening 6 of the wall and on each side of the wall 5 are panels 11 and 12 surrounding the opening 6. The side of the cabinet on the inner side of the wall is closed by the door 13 connected to one side of the panel 11, by suitable hinges 14 and is adapted to swing outwardly from the cabinet. Mounted on the free edge of the door is a suitable spring catch 15 of conventional type, adapted to engage a keeper 16 secured to the panel 11 whereby the door is securely locked, but may be readily opened from the inside of the house or building. The opposite side of the cabinet is equipped with a corresponding door 17 connected to one side of the panel 12, by suitable hinges 18 and also swings outwardly from the wall 5.

50 The door 17 is normally locked in closed position by a latch mechanism consisting of a latch member 19 pivoted intermediate its ends to the side wall 9 of the cabinet, as at 20, one end of the latch member terminating adjacent the inner wall of the door 17 and having a hook 21 formed on its upper edge, 55 adapted to ride under the angularly extending portion 22 of the keeper 23, attached to the door 17, and engage the slot 24 in the portion 22, when the door is closed, thereby locking the door. The wall 9 is provided with a slot 25, at its edge to receive the side 60 of the portion 22 of the keeper when the door is closed. A vertical lever 26, in the form of an angle bar has its lower end pivotally connected to the opposite end of the latch member 19, as at 27, the upper end of the lever being pivotally connected to one 65 end of the lever 28, as at 29. The lever 28 extends substantially horizontally from the lever 26, towards the wall 10 of the cabinet, its opposite end being pivotally connected to the bracket 30, as at 31, depending from the top wall 7 of the cabinet. The lever 28, adjacent its point of pivotal connection with the lever 26 extends through a slot 32 in the bracket 33, depending from the top wall 7, whereby the vertical movement of the lever 28 is limited. The lever 70 75 80 85 90 95 100

Fig. 2 for the greater portion of its length is also in the form of an angle bar having its flange 34 disposed on substantially a hori-

zontal plane, to which a plate 35 is connect-
ed, as at 36, the plate extending laterally
therefrom and having a flange 37, bent down-
wardly from its outer edge, to guide the
5 placing of a milk bottle 37' in the cabinet, so
that the top of the milk bottle will be direct-
ly under the plate 35, as clearly shown in
Fig. 1. Thus, it is seen that the weight of
the levers connected with the latch member,
10 normally hold the latch member in locked en-
gagement with the keeper, preventing open-
ing of the door 17.

A rockable lever 38 is mounted within the
cabinet on the bottom 8, adjacent and par-
15 allel to the wall 9, the inner end 39 of the
lever being bent at right angles to extend
beneath the bottom of a milk bottle placed
beneath the plate 35. The lever 38 is jour-
naled in a suitable bearing 40, attached to
20 the bottom 8, as at 41, and the outer end of
the lever extends beyond the outside of the
cabinet being bent at right angles, in oppo-
site direction to the end 39, providing a suit-
able handle 42 to rock the lever 38, which
25 causes the end 39 to raise the milk bottle
upwardly, the top of the bottle engaging the
plate 35 and actuating the levers connected
with the latch member, so as to unlock the
door 17. When the door is unlocked it is
30 swung open by the leaf spring 43, attached
to the inner side of the door, as at 44, which
extends downwardly so as to lie between
the door and the edge of the bottom 8, when
the door is closed, a recess 45 being formed
35 in the edge of the bottom to receive the
spring.

In use, it will be seen that access to the
cabinet may be had through the inner door
13, at all times, while the outer door 17 is
40 locked against opening from the outside. To
permit opening of the outer door from the
outside, an empty milk bottle is placed in
the cabinet, so that its bottom rests on the
end 39 of the lever 38, directly under the
45 plate 35, whereby actuation of the lever 38,
through the handle 42, raises the bottle, so
that its top engages the plate 35. Upward
movement of the bottle, causes the latch
member 19 to become disengaged from the
50 keeper 23, through operation of the levers
26 and 28, thereby permitting the spring 43
to swing the door 17 open. Thus, it is seen
that the milkman can open the door 17 to
the cabinet, removing the empty milk bottle
55 and placing a full bottle of milk in the cabi-
net to one side of the end 39 of the lever 38,
and upon closing the door 17, access to the
cabinet, except through the inner door 13 is
prevented. This provides safe and sanitary
60 means for receiving milk bottles.

It is to be understood that the form of
my invention herewith shown and described
is to be taken as a preferred example of the
same and that certain changes in the shape,
size and arrangement of the parts may be

made without departing from the spirit of
the invention or the scope of the subjoined
claims.

Having thus described my invention, I
claim:—

1. A milk bottle safe comprising a cabinet,
a closure for said cabinet, a latch member piv-
otally mounted in said cabinet for locking
said closure, a vertical link having one end
pivotaly connected to the free end of said
latch member, a horizontal lever having one
70 end pivotaly connected to the top of said
cabinet and its opposite end pivotaly con-
nected with the upper end of said vertical
link the weight of said link and lever co-
operating to retain said latch member in en-
gaging position, a rockable lever mounted in
75 said cabinet beneath said horizontal lever
having an operating lever extending beyond
said closure, said rockable lever being so
spaced from said horizontal lever that a milk
bottle may be placed between said levers,
80 whereby said horizontal lever and vertical
link may be raised upwardly by said rock-
able lever through the medium of said bottle
releasing said latch member.

2. A device of the class described comprising
a cabinet, a closure therefor, a latch mech-
anism in the cabinet for locking said closure
and normally retained in closure locking po-
sition by gravitation, a rockable lever so
spaced from the latch mechanism that a bot-
85 tle may be placed therebetween and having
an operating handle extending outwardly
from the cabinet, said lever being operable
to actuate said latch mechanism for releasing
the closure when a bottle is positioned in the
90 cabinet between said mechanism and said
lever.

3. A device of the character described com-
prising a cabinet, a closure therefor, a latch
mechanism in the cabinet for locking said
closure and normally retained in closure lock-
ing position by gravitation and means oper-
able outwardly of the cabinet for actuating
100 said latch mechanism through the medium of
a bottle positioned in the cabinet for releas-
ing the closure.

In testimony whereof I affix my signature.

GEORGE RITNER SCHNORE.
